(57) **CLAIM**

The ornamental design for the electronic vaporizer, as described and shown.

DESCRIPTION

FIG. 1 is a front elevational view of the electronic vaporizer; FIG. 2 is a rear elevational view of the electronic vaporizer; FIG. 3 is a top plan view of the electronic vaporizer; FIG. 4 is a bottom plan view of the electronic vaporizer; FIG. 5 is a right side elevational view of the electronic vaporizer; FIG. 6 is a left side elevational view of the electronic vaporizer; FIG. 7 is a perspective view showing the bottom of the electronic vaporizer; FIG. 8 is a perspective view showing the top of the electronic vaporizer; and, FIG. 9 is an enlarged perspective view of a portion of the top of the electronic vaporizer. The broken lines in the drawings depict portions of the electronic vaporizer and form no part of the claimed design
